UNITED STATES PATENT OFFICE.

ETHEL M. BIGSBY, OF DETROIT, MICHIGAN.

SIGN-FRAME.

SPECIFICATION forming part of Letters Patent No. 654,936, dated July 31, 1900.

Application filed March 9, 1900. Serial No. 8,003. (No model.)

To all whom it may concern:

Be it known that I, ETHEL M. BIGSBY, a subject of the Queen of Great Britain, residing in Detroit, in the county of Wayne and State 5 of Michigan, have invented certain new and useful Improvements in Sign - Frames, of which the following is a specification.

This invention relates to an improved sign-frame that is intended to be used in stores— such as dry-goods stores, clothing-stores, and other places in which goods are to be marked clearly and legibly with the price or in which changeable signs are to be put up—so as to indicate the article sold or the price of the 10 same, said sign-frame being so arranged that the individual letters or figures can be readily put together and changed at will with great facility; and the invention consists of a sign-frame which comprises an oblong sup- 15 porting-frame of suitable spring-wire, letters or figures provided at their backs with means for attaching them to said frame, and prongs on said wire frame arranged to project from the same, so as to be attached to the goods for 20 which the sign is to be used.

In the accompanying drawings, Figure 1 represents a front elevation of my improved sign-frame; Fig. 2, a rear elevation of a portion of the same enlarged shown arranged 25 with two letters; and Fig. 3 is a vertical trans-verse section through the frame and sign on line 3 3, Fig. 2.

Similar letters of reference indicate corresponding parts.

Referring to the drawings, A represents an oblong supporting-frame which is preferably made of spring-wire, the ends of which are connected by soldering, twisting, or otherwise, and the side bars $a^1 a^1$ of which are par- 30 allel throughout, while the ends merge into the end bars $a^2 a^2$, which directly connect the ends of said side bars, so that angularly-bent corners a^3 are formed without any shoulders or projections. The frame A is provided with 35 one or more pairs of prongs a , that project in inclined backward direction from the same, so that it can be attached to the goods to be displayed.

To the front part of the wire frame A is applied a number of letters, figures, or other characters B, indicating either the name or character of the goods or the price of the

same, said letters, figures, or other characters being preferably made of cardboard or other suitable material. The figures or other characters are provided at their rear surface with hooks or other suitable fastening devices D D', one hook being applied to the upper bar of the wire frame A and the lower hook to the lower bar of the wire frame, said hooks being bent 55 and curved in opposite direction, so that the fastening-hooks of the letters can be sprung over the parallel side bars on pressing them slightly toward each other and then permitting the side bars of the frame to return to 60 their normal position, whereby the letters can be readily applied to the frame.

A frame of the oblong shape shown and de- 65 scribed will be light and simple, and inasmuch as the end bars directly connect the 70 ends of the side bars in such a manner as that they are no longer than the space between the side bars no shoulders or like obstructions will be formed at the angular juncture of said bars, thus permitting the letters to be slid or 75 slipped onto the ends of the oblong frame, which method of applying the letters to the frame—as, for instance, where the frame is rather rigid or where it is quite flexible—is preferable. A very flexible frame would act 80 in such a way when some of the letters are in position that if others were sprung on the movement of the side bars toward each other would perhaps result in the falling off of some of those already in position.

The fastening devices are applied in any 85 suitable manner to the backs of the letters, figures, or other characters either by means of glue or any suitable fastening means. Either the name or character of the article 90 for which the sign is to be used is set up in suitable letters on the wire frame or the figures forming the price applied thereto, in connection with the dollar-mark or other signs, for which purpose the required number of 95 letters and figures is furnished so as to make up any desired sign required, which is accomplished in a quick and convenient manner. In some cases the sign is not to be attached to the goods, in which case in place of the pointed 100 prongs suitable suspension-hooks may be used, or the frame may be provided with a stay in form of an easel, or it may be made to rest directly against the goods.

The advantages of my improved sign-frame are that signs required in a store can be readily made up from the letters, figures, or characters on hand, in connection with a number 5 of supporting-frames of different sizes, an outfit consisting of a number of frames and letters and characters required for making up the signs being furnished to the parties using the signs, said outfit being comparatively inexpensive, as the goods are made up from cheap material, and yet furnishing a very convenient and attractive sign for the goods to be displayed.

The wire frames are preferably made of 15 black wire, so that the letters or figures appear in very bright manner, while the frames are not visible from a distance.

Having thus described my invention, what I claim as new, and desire to secure by Letters 20 Patent, is—

1. A sign-frame, consisting of an oblong supporting-frame, composed of wire, and the end bars of which are not longer than the space between the side bars, both ends of said

frame being free from any projections or obstructions, and letters, figures or other characters having hooks at their rear, adapted to be slid or strung onto the frame lengthwise thereof, substantially as set forth. 25

2. A sign-frame, consisting of an oblong 30 supporting-frame, composed of wire, and the end bars of which are not longer than the space between the side bars, prongs projecting from said frame, both ends of said frame, at each side of said prongs, being free from 35 any projections or obstructions, and letters, figures or other characters having hooks at their rear, adapted to be slid or strung onto the frame lengthwise thereof, substantially as set forth. 40

In testimony that I claim the foregoing as my invention I have signed my name in presence of two subscribing witnesses.

ETHEL M. BIGSBY.
